UNITED STATES PATENT OFFICE

166,821

LINK CHAIN

Leo R. Pauwels, Los Angeles, Calif.

Application April 7, 1951, Serial No. 14,749

Term of patent 14 years

(Cl. D45—16)

To all whom it may concern:

Be it known that I, Leo R. Pauwels, a citizen of the United States, residing at Los Angeles, in the county of Los Angeles and State of California, have invented a new, original, and ornamental Design for a Link Chain, of which the following is a specification, reference being had to the accompanying drawing, forming a part hereof.

Fig. 1 is a top plan view of a link chain, showing my new design, and

Fig. 2 is a side elevational view thereof.

I claim:

The ornamental design for a link chain, as shown.

LEO R. PAUWELS.
